(57) **CLAIM**

The ornamental design for a submersible camera mask, as shown and described.

DESCRIPTION

FIG. 1 is a front perspective view of a submersible camera mask showing our present invention;

FIG. 2 is a top plan view of the submersible camera mask of FIG. 1.

FIG. 3 is a front elevational view of the submersible camera mask of FIG. 1.

FIG. 4 is a bottom plan view of the submersible camera mask of FIG. 1.

FIG. 5 is a left side elevational view of the submersible camera mask of FIG. 1.

FIG. 6 is a right side elevational view of the submersible camera mask of FIG. 1.

FIG. 7 is a rear elevational view of the submersible camera mask of FIG. 1; and,

FIG. 8 is a top and rear perspective view of the submersible camera mask of FIG. 1.
